ATTORNEY

UNITED STATES PATENT OFFICE

BRUCE E. ROSE, OF EXETER, CALIFORNIA

SCRAPER

Application filed February 9, 1929. Serial No. 338,809.

This invention relates to scrapers of the well known fresno type and particularly to the means for controlling the movement of the bowl.

5 The present invention also relates particularly to the type of control means shown in my co-pending application for patent, Serial No. 155,409 filed December 17th, 1926, and represents improvements thereover in 10 providing a simplified structure which accomplishes the same results with an efficiency equal to that obtained with the previous device.

15 These objects I accomplish by means of such structure and relative arrangement of parts as will fully appear by a perusal of the following specification and claims.

20 In the drawings similar characters of reference indicate corresponding parts in the several views:

Fig. 1 is a perspective view of the scraper in a transporting position.

Fig. 2 is a side elevation of the scraper in the same position.

25 Fig. 3 is a similar view showing the scraper in a loading position.

Fig. 4 is a fragmentary cross-section on the line 4-4 of Fig. 3.

Referring now more particularly to the 30 characters of reference on the drawings, the numeral 1 denotes the scraper bowl of the usual fresno type having a front cutting edge 2. The draft frame for the bowl includes side beams 3 overlapping the sides of the bowl 35 and extending thence forwardly and in converging relation to each other, being adapted at their forward ends for connection to a tractor or other draft means. These beams at their rear ends have longitudinal slots 4 40 in which trunnions 5 are slideable, these trunnions being fixed on and projecting outwardly from the sides of the bowl.

Longitudinally extending bars 6 are disposed between the draft beams and the bowl, 45 said bars at their rear ends being turnably fixed on the trunnions. At their forward ends, a short distance ahead of the bowl, the bars are pivoted on the rearwardly extending lower arms of right angle bellcranks 7 50 which are pivoted onto the beams 3 as at 8.

The upper arms of these bellcranks are provided with laterally and diagonally extending sockets or pads 9 to receive the adjacent ends of the arms 10, which converge thence to a junction with each other at the center 55 of width of the scraper and are there secured to a forwardly extending operating lever 11. These parts are so disposed that when the lower arms of the bellcranks are horizontally disposed or are in longitudinal alinement 60 with the beams 3, the bars 6 are similarly disposed and the trunnions are then adjacent the rear ends of the slots 4. Also the operating lever 11 is then substantially horizontally disposed, as shown in Figs. 1 and 2. 65

The lever 11 is long enough to be operated from the draft means and at its forward end has an upstanding handle portion 11^a so that it can be manipulated when the lever is in a horizontal and lowermost position without 70 the operator having to bend down excessively.

Pivoted in connection with the bars toward their forward ends are upstanding levers 12 having on their lower ends laterally and inwardly extending latch flanges or lips 13 75 adapted to pass under and engage stop or catch pins 14 projecting laterally from the bowl. The upper ends of these levers are connected in common by a cross bail 15 to which a forwardly extending pull rope 16 is attached, so that the lower ends of the levers may be pulled rearwardly to clear the pins, simultaneously and from the draft means to which the scraper is attached. Springs 17 between the levers and bars 6 act to hold the 80 latch flanges engaged with the pins and resist the pull on the rope.

The latch flange and stop pins are so disposed relative to the bars 6 that when said bars are alined with the draft beams the 90 cutting edge of the bowl is clear of the ground and the bowl rides only on its rear end, as shown in Fig. 2.

By reason of the above arrangement of parts it will be seen that the line of draft 95 is from the front end of the beams 3 along said beams to the bellcrank pivots 8, then through the lower arms of the bellcranks and along the bars 6 to the bowl trunnions. Since the natural tendency for said line of draft is to 100

extend in a straight line if possible the bars 6 and the adjacent bellcrank arms will naturally tend to assume and remain horizontal or in longitudinal alinement with the draft beams.

The normal position of the bowl therefore is with its cutting edge tipped up or clear of the ground, since the latch levers are normally engaged with the stop pins, and since the levers are mounted on the movable bars the adjacent portion of the bowl must move up and down with the same. When the lever 11 is thrown up and back the lower arms of the bellcranks are moved down and forwardly, similarly moving the bars 6 and drawing the trunnions forward in the slots. The forward ends of the bars moving down, the latch levers move down also and of course the pins 14 follow up such movement of the latches, since the tendency of the bowl is to always rotate downwardly with the forward movement of the scraper. The forward end of the bowl and the cutting blade will therefore be lowered while the back end or from the trunnions rearwardly will remain at approximately the same level as before, since it is kept from any appreciable change of level by the slots 4 in which the trunnions ride. In fact the slots 4 may have a slight upward stroke from back to front as shown so that the trunnions would be raised somewhat from their original positions, increasing the downward and forward slant of the bowl obtained by reason of the above described movements.

The blade is now contacting with the ground as shown in Fig. 3 and the bowl is in position to load. With the forward movement of the scraper two opposing forces are at work. The frictional engagement of the blade with the ground tends to maintain the bowl tilted forwardly, while the resistance of the bowl as a whole tends to cause the line of draft to straighten out, which would reverse the tilt of the bowl as previously explained. At first the frictional engagement of the blade with the ground exerts a greater force than the resistance of the bowl and it remains in such forwardly tilted position. As the dirt enters the bowl and moves toward the back of the same, the weight of the bowl and its contents and the resistance thereof gradually increases. Also the dirt has a tendency to lower the back of the bowl and rock the same on its trunnions to raise the front end. Finally the resistance of the bowl, aided by the increasing volume and weight of dirt, entirely overcomes the frictional resistance of the blade and the line of draft straightens out completely, lowering the lever 11 to a horizontal position and causing the bars 6 to lie horizontally and the bowl to be moved so that it has a rearward tilt, as previously described. The loaded bowl is therefore in a transporting position without any work on the part of the operator being necessary, though if at any time should he desire to cease loading op-

erations before the bowl automatically tilts, he may easily do it by pulling down on the lever 11. This operation does not require much physical effort, since, as explained, the bowl is itself tending to move to this desired position.

When it is intended to dump the load it is only necessary to pull the rope 16 which allows the bowl to rotate forwardly regardless of the position of the bars 6, the same as described in the previous application.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A scraper comprising a bowl having side trunnions, longitudinally extending draft beams having longitudinal slots through which the trunnions slidably project, arms pivoted at their forward ends onto the beams ahead of the trunnions, bars pivoted at their forward ends on the rear ends of the arms and at their rear ends on the trunnions; said trunnions, when the arms and bars are in straight alinement with each other being disposed toward the rear ends of the slots, means maintaining the bowl normally rigid with the bars and in such relation thereto that the bowl has an upward bottom slope from back to front when the bars are disposed in said straight alinement with the arms, and means for turning said arms downwardly about the pivots to cause the bars to be lowered at their forward ends and the bowl to be likewise lowered at its forward end so that the bottom slope of the bowl is reversed.

2. A structure as in claim 1, in which the draft-beam slots have an upward slope toward their upper ends whereby when the forward ends of the bars are lowered and moved forward and the trunnions are moved forward along the slots, the bottom of the bowl in the longitudinal plane of the trunnions will be raised relative to the beams.

3. A scraper comprising a bowl having side trunnions, longitudinally extending draft beams having longitudinal slots through which the trunnions slidably project, arms pivoted at their forward ends onto the beams ahead of the trunnions, bars pivoted at their forward ends on the rear ends of the arms and at their rear ends on the trunnions; said trunnions, when the arms and bars are in straight alinement with each other, being disposed toward the rear ends of the slots, releasable means between the bowl and bars

toward the forward ends of the latter to normally hold the bowl against forward rotation about its trunnions, said means being arranged to position the bowl so that the bottom thereof has an upward slant from back to front when said arms and bars are thus alined, and an operating lever connected to the arms to turn the latter downwardly and forwardly about their pivotal connections with the beams.

4. A scraper comprising a bowl having side trunnions, longitudinally extending draft beams having longitudinal slots through which the trunnions slidably project, arms pivoted at their forward ends onto the beams ahead of the trunnions, bars pivoted at their forward ends on the rear ends of the arms and at their rear ends on the trunnions; said trunnions, when the arms and bars are in straight alinement with each other, being disposed toward the rear ends of the slots, means maintaining the bowl normally rigid with the bars and in such relation thereto that the bowl has an upward bottom slope from back to front when the bars are disposed in said straight alinement with the arms, and means for breaking such straight alinement downwardly between the pivotal connections of the arms with the beams and the trunnions.

5. A scraper comprising a bowl having side trunnions, longitudinally extending draft beams having longitudinal slots through which the trunnions slidably project, arms pivoted at their forward ends onto the beams ahead of the trunnions, bars pivoted at their forward ends on the rear ends of the arms and at their rear ends on the trunnions; said trunnions, when the arms and bars are in straight alinement with each other, being disposed toward the rear ends of the slots, means maintaining the bowl normally rigid with the bars and in such relation thereto that the bowl has an upward bottom slope from back to front when the bars are disposed in said straight alinement with the arms, and an operating lever connected to the arms to turn the latter downwardly and forwardly about their pivotal connections with the beams; said lever being arranged to extend forwardly and horizontally from said arms when the latter are longitudinally alined with the bars and to be swung upwardly and rearwardly from such position to lower the arms.

In testimony whereof I affix my signature.
55 BRUCE E. ROSE.
